CLAIM

We claim the ornamental design for an audio device, as shown and described.

DESCRIPTION

FIG. 1 is a top perspective view of an audio device showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a bottom rear perspective view thereof.

The broken lines shown are included for the purpose of illustrating portions of the audio device that form no part of the claim.

1 Claim, 8 Drawing Sheets
